(57) **CLAIM**

The ornamental design for a measuring tool, as shown and described.

DESCRIPTION

FIG. 1 is a perspective view of a measuring tool, showing the first embodiment of my new design;

FIG. 2 is another perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof;

FIG. 8 is a perspective view of a measuring tool, showing the second embodiment of my new design;

FIG. 9 is another perspective view thereof;

FIG. 10 is a front elevational view thereof, the rear elevational view being a mirror image of FIG. 10;

FIG. 11 is a left side view thereof;

FIG. 12 is a right side view thereof;

FIG. 13 is a top plan view thereof;

FIG. 14 is a bottom plan view thereof;

FIG. 15 is a perspective view of a measuring tool, showing the third embodiment of my new design;

FIG. 16 is another perspective view thereof;

FIG. 17 is a front elevational view thereof, the rear elevational view being a mirror image of FIG. 17;

FIG. 18 is a left side view thereof;

FIG. 19 is a right side view thereof;

FIG. 20 is a top plan view thereof;

FIG. 21 is a bottom plan view thereof;

FIG. 22 is a perspective view of a measuring tool, showing the fourth embodiment of my new design;

FIG. 23 is another perspective view thereof;

FIG. 24 is a front elevational view thereof, the rear elevational view being a mirror image of FIG. 24;

FIG. 25 is a left side view thereof;

FIG. 26 is a right side view thereof;

FIG. 27 is a top plan view thereof;

FIG. 28 is a bottom plan view thereof;

FIG. 29 is a perspective view of a measuring tool, showing the fifth embodiment of my new design;

(Continued)

FIG. 30 is another perspective view thereof;
 FIG. 31 is a front elevational view thereof, the rear elevational view being a mirror image of FIG. 31;
 FIG. 32 is a left side view thereof;
 FIG. 33 is a right side view thereof;
 FIG. 34 is a top plan view thereof;
 FIG. 35 is a bottom plan view thereof;
 FIG. 36 is a perspective view of a measuring tool, showing the sixth embodiment of my new design;
 FIG. 37 is another perspective view thereof;
 FIG. 38 is a front elevational view thereof, the rear elevational view being a mirror image of FIG. 38;
 FIG. 39 is a left side view thereof;
 FIG. 40 is a right side view thereof;
 FIG. 41 is a top plan view thereof; and,
 FIG. 42 is a bottom plan view thereof.
